CLAIM

The ornamental design for flexible headset for sensing brain electrical activity, as shown and described.

DESCRIPTION

FIG. 1 is a front perspective view of a flexible headset for sensing brain electrical activity showing our new design;

FIG. 2 is a front view thereof;

FIG. 3 is a back view front view thereof;

FIG. 4 is a top view front view thereof;

FIG. 5 is a bottom view front view thereof;

FIG. 6 is a left side view front view thereof; and,

FIG. 7 is a right side view front view thereof.

The broken line(s) which define the bounds of the claimed design form no part thereof.
